ADJUSTABLE CONNECTION FOR DRAW
WORKS GIRT

Wilfred D. Sawyer, Long Beach, Calif., assignor
to Emsco Derrick & Equipment Company,
Los Angeles, Calif., a Corporation of California

Application May 16, 1929. Serial No. 363,697

9 Claims. (Cl. 189—19)

My invention relates to derrick construction and relates particularly to means for connecting a girt to the derrick.

My invention includes a construction which comprehends a jack for moving the girt up or down in combination with means for securely clamping the girt in any one of various positions to the derrick structure.

In the well-drilling industry the derricks are provided with horizontal girts which have secured to them the upper ends of draw-works posts which support various apparatus. There are different makes of this derrick apparatus and the posts are of different lengths; consequently, it is desirable to have the girt adjustable in height.

In my invention the girts may be elevated or lowered to suit the posts.

The angularity of draw-works posts used with the different apparatus may also vary so as to require the draw-works girts supporting the tops of such posts to make connection away from the surface of the derrick legs.

In my invention I have made it an object to provide for the clamping of the girt away from the surface of the derrick leg, both on the outside and inside thereof.

The girt of the derrick to which the draw-works posts are secured is subjected to enormous strains and jerks. My invention provides securing means which rigidly attaches the girt to the derrick, and in the preferred forms of my invention I have devised double securing means which are designed to oppose stresses which are axial or lateral to the girt.

In order that adjustment of the girt may be made without requiring the securing means to be completely removed, my invention comprehends attaching means which, when loosened, permits adjustment of the girt.

My invention further comprehends a jack which will elevate or lower the girt and additionally will clamp the girt from upward movement.

My invention further includes a combination utilizing the double securing means and the clamp means of the jack. These three means cooperate to resist movement of the girt in any direction.

The various features of my invention may be combinatively or separately employed. It should be understood that I do not wish my invention to be narrowly construed as being limited to a structure including every feature outlined above.

In the course of the following description various advantages accruing from the details of construction will appear.

Referring to the accompanying drawings in

which various forms of my invention are illustrated:

Fig. 1 is an elevational view.

Fig. 2 is an elevational view taken as indicated by the arrow 2 of Fig. 1.

Fig. 3 is an enlarged detail taken as indicated by the line 3—3 of Fig. 1.

Fig. 4 is a section taken as indicated by the lines 4—4 of Figs. 2 and 3.

Fig. 5 is an elevational view showing a second form of my invention.

Fig. 6 is an elevational view taken as indicated by the arrow 6 of Fig. 5.

Fig. 7 is a section taken on the line 7—7 of Fig. 5.

Fig. 8 is a fragmentary view taken as indicated by the arrow 8 of Fig. 5.

Fig. 9 is a fragmentary section taken as indicated by the line 9—9 of Fig. 6.

Fig. 10 is a fragmentary plan view partly in section showing a third form of my invention.

Fig. 11 is a view taken as indicated by the arrow 11 of Fig. 10.

Referring to the drawings, I will describe the form of my invention illustrated in Figs. 1 to 4 inclusive.

The numeral 15 represents one of four legs of a derrick. The leg 15 has the cross-section of an angle, as illustrated best in Fig. 3. The lower end of each leg 15 is supported by a suitable base 16, and the various legs are connected together by bracings 17.

Secured to the leg 15 is a primary support 19 and a secondary support 20. The primary support 19 consists of a plate 21 having a portion 22 which engages a flange 23 of the leg 15, and a portion 24 bent at right angles thereto so as to extend inward in a plane parallel to a flange 25 of the derrick leg. The portion 22 of the plate 21 is secured to the flange 23 by suitable rivets 26. The numeral 27 represents a second plate having a portion 28 which extends parallel to the flange 25, and a portion 29 which extends at right angles to the portion 28 and parallel to the flange 23. The plate 27 is secured to the flange 25 of the leg 15 by suitable means such as rivets 30. The portions 24 and 29 of the plates 21 and 27 are secured together by an angle 32 and rivets 33, as shown. The construction just described constitutes the primary support means of the invention. The two plates cooperate to provide a very rigid structure.

The secondary support means of the invention is provided in the shape of an angle. One

flange 35 of the angle 20 engages the portion 28 of the plate 27 and is secured to the flange 25 of the leg 15 by rivets 30. Another flange 36 of the angle 20 extends at right angles to the first flange 35, and the outer face thereof is in the same plane as the plane of the outer face of the portion 22 of the plate 21.

The numeral 38 indicates the girt of the derrick which is to be secured to the leg 15 and a similar leg of the derrick. The girt 38 consists of a channel 40 and a channel 41, which are vertically arranged. These two channels are secured together by a plate 42 which engages the upper flanges thereof and is secured thereto by suitable rivets 43. The channel 41 is shorter than the channel 40 and terminates adjacent to the portion 24 of the plate 21. The channel 40 extends beyond the leg 15 and engages the outer surfaces of the portion 22 of the plate 21 and the flange 36 of the secondary support 20.

For the purpose of securing the girt to the primary and secondary support means I provide the following parts:

Secured to the vertical web of the channel 41 is an attachment angle 45 having a flange 46 adapted to engage an adjacent face of the portion 24 of the plate 21. The portion 24 is provided with a row of openings 47 which are spaced apart equal distances.

Formed in the flange 46 of the attachment angle 45 is a pair of slots 48 which are elongated in the plane which passes through the centers of the row of openings 47. The slots 48 are as long as two openings 47 and the distance 35 between two adjacent openings. The two slots 48 furthermore are spaced apart so that bolts 49 may be passed through the slots 48 and aligned openings 47. Screwed onto the ends of the bolts are nuts 50 which, when screwed in place, will clamp the attachment angle 45 to the portion 24 of the plate 21.

Formed near the end of the channel 40 in a vertical web 52 thereof is a pair of vertically aligned slots 53. Formed in the flange 36 of the support member 20 is a row of vertically aligned openings 54. The slots and openings 53 and 54 correspond in position to the slots and openings 48 and 47. Extended through each slot and one opening is a bolt 55 having a nut 56 screwed on the end thereof for clamping the web 52 of the channel 40 against the flange 36 of the secondary support 20.

The two securing means just described are disposed so that the bolts 49 and 55 extend at right angles to each other. One securing means is adapted to primarily resist strains acting in a plane parallel to the girt, and the other securing means is adapted to resist strains which act in a horizontal plane at right angles to the axis of the girt. In view of the fact that enormous strains and jerks are imposed on the girt, it is quite essential to have very rigid securing means, and my invention provides securing means which are adequate for the occasion.

For the purpose of adjusting the vertical position of the girt 38 I provide jack means which will now be described. Secured to the portion 24 of the plate 21 at a position centrally between the adjacent portions of the channels 40 and 41 is a bracket 58. The bracket 58 has a portion 59 which is secured by rivets 60 to the portion 24 of the plate 21 and has a horizontally extending bracket-flange 61. Extended through openings 62 formed in the flange 61 on a plane parallel to the portion 24 is a pair of jack screws 63. Heads

64 of the jack screws engage the lower face of the flange 61, and clamp nuts 65 threaded onto the jack screws 63 engage the upper face of the flange 61. The jack screws extend in parallel relation and the upper ends thereof extend through openings 67 formed in the plate 42 and openings 68 formed in a bar 69 secured by rivets 70 to the plate 42 and to the channels 40 and 41. Screwed onto the jack screws 63 and engaging the lower face of the plate 42 are jack nuts 71, and advanced onto the upper ends of the jack screws 63 and engaging the upper face of the bar 69 are hold-down nuts 73. When the girt is clamped in a certain position, the jack nuts 71 and the hold-down nuts 73 cooperate to resist any forces which tend to move the girt in a vertical plane. The bar 69 and the contiguous part of the plate 42 constitute a girt-flange.

When it is desired to adjust the vertical position of the girt 38, it is necessary to loosen the nuts 50 and 56 on the bolts 49 and 55. When this has been done, the hold-down nuts 73 are advanced upward so as to release the grip on the plate end bar 42 and 69; the jack nuts 71 are then advanced either upward or downward on the jack screw 63 until the girt is properly positioned. Due to the fact that the slots 48 and 53 are provided, it is possible to have a relative movement between the bolts and the girt. The slots are of such a length and are so spaced that the girt may be moved downward so that the slot aligns at its upper end with one opening and at the lower end with another opening. This permits the bolt to be removed and extended through the lower opening so that the girt may be further dropped or raised, as the case may be, if necessary. By this arrangement, it is possible to always have the bolts in position to be tightened and to prevent the girt from dropping should any trouble occur in the jack means of the invention. When the girt has been properly positioned, the nuts are screwed into place so as to clamp the girt to the primary and secondary supports and the hold-down nuts 73 are advanced downward so that the plate and bar are tightly clamped between the jack nuts 71 and the hold-down nuts 73.

It will of course be understood that the other end of the girt and the adjacent leg of the derrick are provided with similar securing means supports, and jacks, and during this adjustment the corresponding parts at the other end of the girt must also be operated.

One of the important features of the form of the invention just described is that the end of the girt 38, namely the end of the channel 40, engages the portion 22 of the plate 21 and the secondary support 20. These parts provide ample bearing surfaces and, being directly and immediately connected to the leg, very rigidly support the girt.

I will now describe the form of my invention shown in Figs. 5 to 9 inclusive.

In this form of the invention the girt 38 is composed of channels 80 and 81. The inner channel 80 is longer than the outer channel 81, and the end thereof projects outward beyond the leg 15. The two channels are connected together at the end of the outer channel 81 by means of a channel plate 82, the flanges of which are secured to the channels 80 and 81 by rivets 83. Secured to the flange 23 of the leg 15 by rivets 85 is a secondary support 86 having a portion 87 and a portion 88, which portions are bent at right angles to each other. The portion

88 of the secondary support 86 extends into contact with the surface of the plate 82. Two vertical rows of openings 90 and 91 are formed in the portion 88, these openings being vertically spaced apart a certain distance. Formed in the plate 82 are slots 92 and 93 which are arranged in pairs and in alignment with the rows of openings 90 and 91. Adapted to extend through each slot 92 and 93 and adjacent openings 90 and 91 are bolts 94. The slots and openings are of the same arrangement and character as the slots and openings described in the first form of my invention.

Secured to the flange 25 of the leg 15 is a primary support in the form of a plate 96. The plate 96 has a portion 97 and a portion 98, which extend in planes at right angles to each other. The portion 98 is adapted to engage the inner face of a vertical web 99 of the channel 80. Formed in the portion 98 is a row of openings 100, and formed in the end of the channel 80 is a pair of slots 101 which are vertically aligned and which are in alignment with the row of openings 100. Adapted to extend through each slot 101 and one of the openings 100 are bolts 102. These openings and slots 100 and 101 bear the same relation to the slots 90 and 91 and 92 and 93 as do the pairs of openings and slots in the first form of my invention.

Secured to the lower part of the portion 98 is an angle bracket 104. The angle bracket has a horizontal leg 105 through which a jack screw 106 is extended. A head 107 of the jack screw engages the lower face of the leg 105, and a clamp nut 108 is advanced onto the jack screw 106 and engages the upper face of the leg 105. Formed in horizontal flanges 110 of the channel 80 are vertically aligned openings 111 through which the jack screw extends. Engaging the lower face of the lower flange is a jack nut 112, and engaging the upper face of the upper flange 110 is a hold-down nut 113.

This form of my invention is designed for girts which are spaced away from the legs of the derrick. In the form shown, the girt is spaced a distance inside the derrick. It will be seen, however, that by inverting the parts and extending them in opposite directions it is possible to support the girt in a position outside the derrick.

The adjustment of this form of the invention and the features thereof are substantially the same as described with respect to the first form of my invention. When the bolts 94 and 102 are loosened, the jack screw may be operated and the girt may be raised or lowered, as desired, it of course being understood that the hold-down nut 113 must be loosened before the jack nut is operated. The slots 92 and 93 and 101 permit the girt to slide vertically without removing the bolts, and if the distance the girt is to be moved is greater than the length of the slot the bolts may be extended through different openings.

In Figs. 10 and 11 I show a third form of my invention which I will now describe.

Secured to the flange 23 of the leg 15 is a primary support having a plate 120 which is secured in place by rivets 121. The right end of the plate 120 has a pair of angles 122 secured thereto by rivets 123. Attached to the angles 122 by bolts 125 is a bracket 126 through a horizontal flange 127 of which jack screws 128 are extended. The jack screws 128 have heads 130 and have clamp nuts 131 which engage the horizontal leg 127 of the bracket 126, thus clamping the jack screws 128 securely thereto. The girt used in

this form of the invention is of the same construction as the girt illustrated in Figs. 1 to 4 inclusive. The jack screws extend upward through the openings formed in the plate 42 and the bar 69. Adapted to engage the upper and lower surfaces of these parts are the jack nuts 71 and the hold-down nuts 73.

In this form of the invention I utilize a secondary member 20 which is of the same design as utilized in the first form of my invention illustrated in Figs. 1 to 4 inclusive, the only difference being that the flange 35 thereof is longer, so that the flange 36 is spaced in a plane a distance to the outside of the derrick and away from the flange 23 of the leg 15. The flange 36, as illustrated in the first form of my invention, is provided with the openings 54, and the end of the channel 40 is provided with the slots 53. Bolts 55 having nuts 56 screwed thereon are also utilized.

In this form of the invention the manner of adjustment is identical with that of the first form of my invention. This form as described is adapted for use where the girt is to be placed a short distance outside the derrick, but, by inverting the parts and extending the secondary member 20 in the opposite direction, the girt 38 may be supported on the inside of the derrick leg 15.

I claim as my invention:

1. In an adjustable girt construction, the combination of: a derrick leg; a girt member adapted to be supported by said leg in a plurality of positions; a primary support member rigidly secured to said leg and being supported thereby; jack means operatively connected to said primary support and to said girt whereby said girt may be moved into different positions relative to said leg; and a secondary support member secured to said leg and to said girt for rigidly securing same together.

2. In an adjustable girt construction, the combination of: a derrick leg; a girt member adapted to be supported by said leg in a plurality of positions; a primary support member rigidly secured to said leg and being supported thereby; jack means operatively connected to said primary support and to said girt whereby said girt may be moved into different positions relative to said leg; a secondary support member secured to said leg and having a plate along which said girt is slideable; and means for securing said girt to said plate.

3. In an adjustable girt construction, the combination of: a derrick leg, a girt member adapted to be supported by said leg in a plurality of positions and having a recess near the end thereof through which said leg extends; a primary support member rigidly secured to said leg and being supported thereby; jack means operatively connected to said primary support and to said girt whereby said girt may be moved into different positions relative to said leg; and a secondary support member secured to said leg and to said girt for rigidly securing same together.

4. In an adjustable girt construction, the combination of: a derrick leg; a girt member adapted to be supported by said leg in a plurality of positions and having a recess near the end thereof through which said leg extends; a primary support member rigidly secured to said leg and being supported thereby; jack means operatively connected to said primary support and to said girt whereby said girt may be moved into different positions relative to said leg; a secondary support member secured to said leg and having

a plate along which said girt is slidale; and means for securing said girt to said plate.

5. In an adjustable girt construction, the combination of: a derrick leg; a girt member adapted to be supported by said leg in a plurality of positions and having a recess near the end thereof through which said leg extends; a primary support member rigidly secured to said leg and being supported thereby; jack means operatively connected to said primary support and to said girt whereby said girt may be moved into different positions relative to said leg; a secondary support member secured to said leg and having a plate along which said girt is slidale; and means for securing said girt to said plate, said primary support member being on one side of said recess and said secondary support member being on another side of said recess.

6. In an adjustable girt construction, the combination of: a derrick leg; a girt member adapted to be supported by said leg in a plurality of positions and having a recess near the end thereof through which said leg extends; a primary support member rigidly secured to said leg and being supported thereby; jack means operatively connected to said primary support and to said girt whereby said girt may be moved into different positions relative to said leg; a secondary support member secured to said leg and having a plate along which said girt is slidale; and means for securing said girt to said plate, said primary support member being on one side of said leg and said secondary support member being on another side of said leg.

7. In an adjustable girt construction, the combination of: a derrick leg; a girt member adapted to be supported by said leg in a plurality of positions; a primary support member rigidly secured to said leg and being supported thereby; jack means operatively connected to said primary support.

port and to said girt whereby said girt may be moved into different positions relative to said leg; primary securing means for securing said girt to said primary support member; and a secondary support member secured to said leg and to said girt for rigidly securing same together.

8. In an adjustable girt construction, the combination of: a derrick leg; a girt member adapted to be supported by said leg in a plurality of positions and having a recess near the end thereof through which said leg extends; a primary support member rigidly secured to said leg and being supported thereby; jack means operatively connected to said primary support and to said girt whereby said girt may be moved into different positions relative to said leg; primary securing means for securing said girt to said primary support member; and a secondary support member secured to said leg and to said girt for rigidly securing same together.

9. In an adjustable girt construction, the combination of: a derrick leg; a girt member adapted to be supported by said leg in a plurality of positions and having a recess near the end thereof through which said leg extends; a primary support member rigidly secured to said leg and being supported thereby; jack means operatively connected to said primary support and to said girt whereby said girt may be moved into different positions relative to said leg; primary securing means for securing said girt to said primary support member; a secondary support member secured to said leg and having a plate along which said girt is slidale; and means for securing said girt to said plate, said primary support member being on one side of said recess and said secondary support member being on another side of said recess.
